UNITED STATES PATENT OFFICE

ALBERT L. NEWMAN, OF MEMPHIS, TENNESSEE.

AUTOMATIC TRAIN-STOP.

1,349,525.

Specification of Letters Patent. Patented Aug. 10, 1920.

Application filed July 22, 1919. Serial No. 312,566.

To all whom it may concern:

Be it known that I, ALBERT L. NEWMAN, a citizen of the United States, residing at Memphis, in the county of Shelby and State 5 of Tennessee, have invented certain new and useful Improvements in Automatic Train-Stops, of which the following is a specification.

This invention has reference to automatic 10 devices for stopping trains, and particularly to means for stopping a train in the event of derailment of any of the units of the train.

The object of the invention is to provide 15 means connected with the air brake system of a train for automatically releasing the air and stopping the train, should any one of the cars or the engine become derailed; the invention being capable of application 20 to freight or passenger cars without any material alteration in the construction, and fulfilling the intended purpose in an effective manner.

The invention consists in the novel construction and combination of parts herein-after particularly set forth and pointed out in the claims; it being understood that while the drawing shows the preferred embodiment of this invention, I do not wish to be limited to the exact construction, but desire to make such changes in the form, size, proportion and minor details of construction as will come within the scope of the appended claims.

35 In the drawing:—

Figure 1 is a side elevation of so much of a railway truck as seems necessary to disclose in order to show the application of my invention thereto;

40 Fig. 2 is an end view of the same;

Fig. 3 is a detail view looking at the front, with parts in section, illustrating the bracket carrying the stop cock;

Fig. 4 is a vertical sectional view of the 45 same.

Like reference characters designate corresponding parts in the several figures of the drawing.

Referring to the drawing, I have shown 50 in Figs. 1 and 2, a railway truck of ordinary construction with my invention applied thereto. As the truck forms no part of this invention, it will only be incidentally referred to.

55 1 designates the train line air pipe of the air brake system employed on railway

trains, provided at a point thereon with a T 2, to which is secured a branch pipe consisting of a short length of pipe 3, and a section of hose 5, which leads to a stop cock 6. A standard cock 4 connects the pipe 3 and hose 5. The stop cock 6 shown in detail in Figs. 3 and 4, is mounted in the offset arm 14 of a bracket 7, rigidly mounted on one of the beams of the truck in the manner shown. This stop cock consists of an inwardly tapered plug 6^a, which is mounted for rotary movement in a correspondingly tapered opening or seat of the offset arm 14 of the bracket 7, and has its inner 60 end extended beyond said arm and provided with a polygonal projection 8, to which is rigidly fitted the enlarged head 9 of a lever arm 10, the latter being retained in place by means of a cotter key, which is fitted in the two holes of the parts 8 and 9. At the other 65 or outer end of the plug of the stop cock a pocket 11 is provided in which is placed a coiled spring 12, held in position by a screw cap 13, as shown in Fig. 4. The purpose of 70 the screw cap and coiled spring is to insure a tight fit for the valve.

The offset arm 14 has at each side of the turning plug of the cock 6, short tubular extensions 15 and 16 which are internally 75 threaded. Fitted in the extension 16 is a screw plug 17 having a longitudinal opening 18, while the extension 15 receives the threaded end of the hose nipple 19, the latter being provided to receive the lower end 80 of the hose 5.

The extensions 15 and 16 have longitudinal ports 20 and 21, respectively, which are brought into and out of register with the transverse port 22 provided in the turning plug 6^a of the stop cock 6; it being understood that when the port 22 of the said plug 6 is in register with the ports 20 and 21, the air from the train line pipe may escape or "bleed" through the opening 18 of 100 the screw plug 17. The turning plug 6^a of the cock 6 has its port 22 normally out of register with the ports 20 and 21, respectively. The means by which said plug is turned or operated to effect this change of 105 position will now be referred to.

The lever arm 10, which is rigidly connected to the inner end 8 of said turning plug, has its outer end adjustably connected to the upper end of a pivoted link 23, the 110 lower end of which is connected at or about the center to a transversely disposed operat-

ing bar 24, the central portion of which is bowed, as shown, while the two ends extend in straight lines and normally lie in a plane above the rails of a track, and between the 5 wheels of the truck, as shown in Fig. 2, of the drawing.

Rising from the straight ends of said operating bar 24 in rear of the terminals thereof are two vertically disposed guide arms 10 25, one at each side, which work in openings of guide brackets 26 secured to one of the rigid beams or members of the truck. As shown in Fig. 2, the guide brackets 26 have tapered openings 29, being larger at the top 15 than at the bottom, the purpose of which is to provide clearance to keep the guide arms 25 from binding, should one end of the operating bar 24 be raised higher than the other end. The said openings in the guide 20 brackets are oblong at the top and circular at the bottom so as to hold the guide bars steady and prevent any sidewise movement.

In order to set the operating bar 24 the correct distance from the rail, holes 27 are 25 provided in the upper ends of the guide arms 25, and pins 28 are passed through the holes and across the upper ends of the guide brackets 26, to support the operating bar from dropping down. The adjustment 30 provided in the guide arms 25 necessitates a corresponding adjustment in the connection between the link 23 and the lever arm 10.

The operation of this invention will be obvious to anyone skilled in the art. Under 35 normal conditions the operating bar 24 is supported at a height of several inches above the rails and between the wheels, and below the plane of the axle as shown in Figs. 1 40 and 2 of the drawings. In the event of the breakage of a car truck, a car axle, or in case of derailment, the car will drop relatively to the track, and the straight ends of the operating bar 24 will contact with the 45 upper faces of the rails. In doing this, the link 23 will be actuated to swing the lever arm 10, and turn the turning plug of the stop cock, causing the port 22 thereof to register with the ports 20 and 21, resulting 50 in the air being released and bringing the train to a stop. It will be noted that by

the provision of the hole 18, which is $\frac{3}{8}$ of an inch in diameter, provided in the plug 17, said hole being of considerably less diameter than the port of the plug, the air is let out 55 slowly, which prevents the application of the emergency brake.

The purpose of providing the stop cock 4 which is of standard construction, is to provide for cutting out the air at that point 60 in case of an accident should the stop cock 6 become disabled.

It will be noted that the mechanism may be applied to a truck without making any alteration in the construction thereof, as 65 the guide bracket 26 and the supporting bracket 7 may be fitted to any truck.

What I claim is:—

1. In a valve adapted to be applied to a car truck and to be connected with an air 70 brake, the combination with a bracket supported on said truck, a plug detachably and revolvably mounted on said bracket and having a transverse port, said bracket having a pair of ports contiguous to said plug, said 75 pair of ports being brought into and out of communication with the port of said plug by the turning movement of the latter, a perforated plug fitted to the bracket and having its perforation in communication 80 with one of said pair of ports, and of less diameter than the same, a nipple fitted to the other one of said pair of ports, and means connecting the nipple to the train 85 line pipe.

2. The combination with a railway truck, a train line pipe and a stop cock of an operating bar for opening and closing said stop cock, said bar being supported transversely above the rails of a track and below 90 the plane of the axle of said truck, vertically disposed guide arms rising from said bar near opposite ends, guide brackets mounted upon the truck and having openings through which the guide arms extend, 95 and means for vertically adjusting said guide arms, the openings of said guide brackets gradually increasing in width toward the top, for the purpose set forth.

In testimony whereof I affix my signature. 100

ALBERT L. NEWMAN.
